UNITED STATES PATENT OFFICE

2,413,519

ELECTRICAL PLUG AND SOCKET CONNECTION

Harry Wilbur Reed, Cincinnati, Ohio

Application November 15, 1943, Serial No. 510,345

1 Claim. (Cl. 173—330)

1

The present invention relates to improvements in electrical connections and has for an object thereof to provide an electrical connection of the plug and receptacle type wherein the plug will make electrical connection with the socket in all angular positions thereof.

Another object of the invention is the provision of an electrical connection of the aforesaid character designed so that the plug may be quickly and easily fitted in connecting position and will be firmly and detachably associated with the socket.

A further object of the invention is the provision of a plug and receptacle connection of the above character which is relatively simple and durable in construction and efficient in use.

Other objects and advantages of the invention will become apparent as the description progresses.

In the accompanying drawing forming a part of this specification and in which like numerals are employed to designate corresponding parts throughout:

Figure 1 is a view partly in longitudinal elevation and partly in section,

Figure 2 is an inner end view of the receptacle with the plug attached thereto,

Figure 3 is an end view of the plug, and

Figure 4 is a fragmentary view showing the receptacle in exterior elevation.

Referring in detail to the drawing, wherein for the purpose of illustration is shown a preferred example of the invention, 10 generally designates a plug body in the form of a conoidal frustum formed of electrical insulating material and having the reduced inner end connected with a two wire insulated conductor 11. The end face of the outer larger end of the body 10 is formed with an annular groove 12 of rectangular cross section concentric with the plug center having tightly fitted therein a ring 13 of current conductive material also of rectangular cross section. The outer edge of the ring 13 is exposed at and may advantageously project from the end face of the plug.

A straight length of round bar current conducting material 14 is mounted so that approximately one half its length is disposed axially in the plug body while the remaining portion protrudes outwardly of the body as shown to advantage at Figure 1. The inner end of the conducting bar 14 is flattened as indicated at 15 and connects with a wire 16 by soldering or other suitable connection. The outer end of the bar member 14 may be advantageously rounded and is

2

provided adjacent thereto with an annular groove 15.

The receptacle to which the plug is to be connected, generally indicated at R embodies a base plate 19 constructed of insulating material and provided with an opening 20 designed to slidably receive the protruding or prong portion of the contact bar 14 therethrough. At its inner side the plate 19 is formed with a tubular guide sleeve 21 having its bore in registration with the opening 20 and, in a position spaced from this sleeve, the inner side of the plate is provided with a boss 22 in which is provided a screw receiving interiorly threaded bore 23. At the opposite side of the sleeve 21 the plate is formed with an inwardly projecting tubular socket 24 interiorly threaded at its outer end as indicated at 25. The bore of the socket 24 is in registration with and of greater diameter than an opening 26 through the plate, the purpose of which will be described hereinafter.

In the opening 26 is slidably fitted a contact pin 27 of conducting material formed at its inner end with an enlarged round head 28 slidable in the bore of the socket and having a diameter greater than that of the opening 26.

An exteriorly threaded bushing element 29 of conducting material, provided with an interiorly threaded screw bore is screwed into the outer end of the socket 24 and serves to maintain a coiled spring 30 of conductive material under compression within the socket between the inner end of the bushing and the head 28 of the contact pin. A binding screw 31, which may be of conventional construction, engages the bore of the bushing 29 and connects a branch circuit wire 32 therewith.

The bore 23 disposed transversely of the receptacle plate 19 is adapted to receive therein the shank of a terminal screw 33 which extends through one apertured end of a flat contact bar 34 of conducting material. This bar 34 is disposed so that the major length thereof extends inwardly from the boss 22 at an acute angle with the plate 19 and has an arcuately bent outer end portion 35 adapted to resiliently engage the groove 12 in the prong forming portion of the rod 14. The terminal screw 33 also functions to connect a branch circuit wire 36 with the inner apertured end portion of the contact bar 34.

As illustrated at advantage at Figure 1 the shank of the contact pin 27 has a length substantially exceeding the thickness of the receptacle plate 19 so that the outer end thereof is yieldingly pressed to protruding position by the

spring 30. This figure also shows the soldered connection of one of the wires 31 of the plug 10 with the contact ring 13.

As will be readily apparent the plug section 10 of the connection may be fitted in electrical union with the receptacle section R by aligning the rounded front end of the prong forming axial projection of the center contact bar 14 with the receptacle opening 20 and sliding the outer face of the plug toward the receptacle plate 19. During the final stages of this connection the prong will contact with the contact bar 34 and the arcuate outer end thereof will enter the groove 35 to connect the wire 16 of the plug with the wire 36 of the branch circuit and to frictionally hold the plug in association with the receptacle. As the plug face approaches the receptacle plate 19 the ring 13 will be brought into contact with the spring pressed contact pin 27 and retract the pin against the action of the spring 30 so as to complete the circuit through the spring, the bushing 29 and the binding screw 31 to electrically join the wires 32 and 37.

It is to be understood that the form of my invention herewith shown and described is to be taken as a preferred example of the same and that various changes relative to the material, size, shape and arrangement of parts may be

resorted to without departing from the spirit of the invention or the scope of the subjoined claim.

Having thus described my invention, I claim:

In an electrical connection, the combination of a plug body, a prong protruding from the outer end of the body and having its inner end connected with a conductor in the plug, a contact ring fitted in a groove in the said outer end of the plug and disposed concentrically of the prong, the said contact ring being electrically connected with a second conductor in the plug and having its outer edge exposed with relation to the outer end of the plug, a receptacle plate having a passage adapted to slidably receive the prong there-through, a groove adjacent the end of said prong, a contact bar mounted on the plate in contact with a conductor, the outer end of the said contact bar being disposed to make resilient contact with the groove in the prong by reason of the arcuately, bent outer end portion of said bar, a contact pin mounted to slide transversely of the plate within an opening therein, a spring mounted on the plate disposed to yieldingly project the pin so that its outer end protrudes therefrom for engagement with the contact ring, and means electrically connecting the said pin with a second conductor on the receptacle.

HARRY WILBUR REED.
